Int. Cl. D14—03

U.S. Cl. D56—4

FIG. 1

FIG. 2

FIG. 3

FIG. 1 is a front, top and right side perspective view of a radio cabinet, showing one form of our new design wherein the pedestal is square in horizontal cross-section;

FIG. 2 is a front elevational view of a radio cabinet, showing a second form of our new design wherein the pedestal is round in horizontal cross-section; and

FIG. 3 is a left side elevational view of the form shown in FIG. 2, the right side being substantially a mirror image thereof.

Portions of the drawing figures are shaded to indicate contrast in appearance, and portions are diagonally lined to indicate transparency.

We claim:

The ornamental design for a radio cabinet, substantially as shown and described.
